TUMBLER OR SIMILAR ARTICLE

Donald R. Neil, Short Hills, N.J., assignor to Paul A. Straub and Company, Inc., New York, N.Y., a corporation of New York

Filed Nov. 17, 1964, Ser. No. 82,660

Term of patent 7 years

(Cl. D36—8)

Fig-1

FIGURE 1 is a side elevational view of a tumbler or similar article embodying my design;

I claim:

The ornamental design for a tumbler or similar article, substantially as shown.
